DESIGN FOR A ROAD SIGN FOR RAILWAY CROSSINGS

Lorne M. Bradley, Toronto, Ontario, Canada, assignor to St. Thomas Metal Signs Limited, St. Thomas, Ontario, Canada

Application November 10, 1934, Serial No. 53,962

Term of patent 3½ years

To all whom it may concern:

Be it known that I, Lorne M. Bradley, a subject of the King of Great Britain, and resident of the city of Toronto, county of York, Province of Ontario, in the Dominion of Canada, has invented a new, original, and ornamental Design for a Road Sign for Railway Crossings, of which the following is a specification, reference being

had to the accompanying drawing, forming part thereof.

The figure is a perspective view of a road sign for railway crossings showing my new design.

I claim:

The ornamental design for a road sign for railway crossings substantially as shown.

LORNE M. BRADLEY.
